US00D743084S

(12) **United States Design Patent**
Lay et al.

(10) **Patent No.:** **US D743,084 S**
(45) **Date of Patent:** **** Nov. 10, 2015**

(54) **LIGHT FIXTURE**

(71) Applicant: **Cree, Inc.**, Durham, NC (US)

(72) Inventors: **James Michael Lay**, Apex, NC (US);
Don Miletich, Franklin, WI (US)

(73) Assignee: **Cree, Inc.**, Durham, NC (US)

(**) Term: **14 Years**

(21) Appl. No.: **29/514,861**

(22) Filed: **Jan. 16, 2015**

(57) **CLAIM**

The ornamental design for a light fixture, as shown and described.

DESCRIPTION

FIG. 1 is a perspective view of the light fixture; FIG. 2 is a bottom plan view of the light fixture of FIG. 1; FIG. 3 is a top plan view of the light fixture of FIG. 1; FIG. 4 is a right-side elevation of the light fixture of FIG. 1, the left-side elevation view being a mirror image thereof; and, FIG. 5 is a front elevation of the light fixture of FIG. 1, the rear elevation being a mirror image thereof. The phantom lines are provided for illustrative purposes only and form no part of the claimed design.

1 Claim, 4 Drawing Sheets
